METHOD AND APPARATUS FOR THE RE-
GENERATION OF PRESERVED FOODS,
NUTRIMENTS, AND LIKE MATERIALS

Siegwart Hermann, New York, N. Y.

Application November 22, 1941, Serial No. 420,058

9 Claims. (Cl. 99—182)

It is known to preserve foods, nutriments and like materials by hermetically enclosing them in vessels, cans or the like, and heating them up to approximately 100—125° C. At these temperatures the micro-organisms and their germs lose permanently their viability and are completely destroyed. The material so treated becomes sterile and remains lastingly preserved.

This heat-treatment of the said substances has the disadvantage, that the heat destroys many of their original ingredients which are vital for life, such as vitamins, hormones and enzymes so that their nutritive value is diminished in an undesired degree. This heat-treatment makes it also impossible to add to the foods, nutriments and similar materials which have to be prescribed, such substances which are unable to resist the applied heat. Such additions are sometimes desirable for dietary and/or therapeutic purposes.

The main object of my invention is to prevent the above mentioned disadvantages and to overcome the aforesaid difficulties by rendering it possible to include non-heat-resistant substances, which are vital for life and/or desirable for dietary or therapeutic purposes, in foods, nutriments or like materials which have been preserved in hermetically closed vessels or cans by heat-treatment.

My invention consists basically therein, that the non-heat-resistant substances which are vital for life such as vitamins, hormones and enzymes, and/or other non-heat-resistant substances desirable for dietary or therapeutic purposes are injected into the hermetically closed vessels or cans after their heat-treatment by means of an injection needle whereupon the perforation caused by the needle is again hermetically closed. These operations are preferably performed in a sterile space or chamber. The closing of the needle-prick can be made by soldering, welding or similar means and every vessel or can may be heated separately or two or more vessels or cans may be treated simultaneously in groups.

The novel features that I consider characteristic of my invention are set forth with particularity in the appended claims. The invention itself, however, both as to its organization and method of operation, together with additional objects and advantages thereof, will best be understood from the following description of an apparatus chosen out of many possible forms when read in connection with the accompanying drawing, in which

Fig. 1 shows a view, partly in section on the line 1—1 of Fig. 3;

Fig. 2 is a side view, partly in section on the line 2—2 of Fig. 1;

Fig. 3 is a top view beneath the line 3—3 of Fig. 1; and

Fig. 4 is a partial top view corresponding to Fig. 2.

The vessels, cans or the like 1 are transported from left to right by a chain or a plurality of chains or a chain-grate 2 from a fixed table 3 over a working table 4, which can be raised and lowered, to the fixed table 5. The vessels 1 are so set in the chain-meshes that they may move up and down according to the up and down movements of the working-table 4, which rests on the piston-rods 7 of hydraulic or similar cylinders 6.

The working table-plate 4 forms the bottom of a tunnel shaped chamber 8, which is surrounded by the side-walls 9 and the ceiling plate 10. Above the left half of this ceiling-plate 10 lies a tank 11, which is connected with an installation to put the liquid in the tank under pressure, this installation consisting, for example, of the cylinder 12 in which a piston 13 may be moved. The tank 11 may be refilled from a store tank 14 through the pipe 15 which contains a valve 16.

30 The ceiling-plate 10, as far as it forms the bottom of the tank 11, bears injection-needles 17 which are so arranged that always one needle lies over a vessel or can 1. In the same manner are electric welding or soldering rods or wires 18 arranged in the right half of the channel-ceiling 10.

The table-plate 4 bears U-shaped stirrups 22 which embrace the cans 1 and take them down with the table-plate 4.

40 Fuel or gas pipes 20, 21 are arranged at the entrance and outlet openings of the tunnel-shaped chamber 8. The fuel or gas emanates from these pipes 20, 21 in such a manner that, when burning, a flame wall is formed which closes the chamber in a sterile manner against the exterior. This flame wall causes also a sterilization of the surface of the vessels or cans 1 while they traverse through the flame before being treated in the chamber 8.

45 50 The process is performed in the following manner:

The vessels or cans 1 which contain the preserved foods, nutriments or the like, are put in the meshes of the transport chain 2, and trans-

ported from the table 3 into the chamber 8. On this way the cans 1 pass through the flame wall emanating from the pipe 20 so that their surface is sterilized. The outlet end of the chamber 8 is closed by the flame-wall emanating from the pipe 21, so that the chamber-space 8 remains sterilized.

According to the specific embodiment shown in the drawing, four rows each containing four cans are in the beginning brought into the chamber 8, so that always one can is situated beneath an injection-needle 17.

Then the working-table 4 is raised according to the arrow 23 and the cans 1 are pressed against the injection-needles 17 which penetrate through the vessel-walls. Thereupon the liquid contained in the tank 11 is injected under pressure caused by the piston 13 through the injection-needles 17 into the cans 1. This liquid contains those substances which have to be introduced in the cans such as vitamins, and/or hormones and/or enzymes and/or other substances desirable for dietary or therapeutic purposes.

After completion of this injection the working-table 4 with the cans is again lowered and the cans which just have been treated are transported beneath the soldering or welding rods 18. Simultaneously new cans are brought under the injection-needles 17 in the left half of the channel.

Now the working-table 4 is again raised so that the new cans may be treated as described before and that simultaneously the needle-pricks in the cans now situated under the soldering or welding rods 18 may be closed.

Thereafter the working-table 4 is again lowered and the described acts may be repeated. The cans treated according to the invention are removed above the table 5 from the transport chain 2.

It may be noted that, as used in this specification and in the claims, the term "can" includes any hermetically closed vessel, which may be used for the preservation of foods, nutriments and similar materials, and which is in whole or in part made from a material that can be perforated by a needle.

The term "canned foods" includes any foods, nutriments, dietary substances and the like, which are hermetically enclosed in cans and then have been sterilized by heat.

Having described and illustrated one form of my invention, I wish it to be understood that my invention is not to be limited to the specific form or arrangement of parts herein described and shown, or specifically covered by my claims.

What I claim is:

1. An apparatus for inserting accessory ingredients into the sterilized contents of sealed containers which comprises a sterile working chamber, an accessory feeding device capable of penetrating the container wall and a device for sealing said opening.

2. An apparatus for inserting accessory ingredients into the sterilized contents of sealed containers which includes a sterile working chamber and within this chamber a puncturing device to penetrate the container wall, an inserting device for introducing accessory ingredients through the

puncture, and a sealing device for reclosing the opening.

3. An apparatus for inserting accessory ingredients into the sterilized contents of sealed containers which includes means for sterilizing the surface of the sealed containers before they are introduced and operated upon in a sterile working chamber, and within this chamber a feeding device for puncturing the container wall and inserting accessory ingredients into the container, and a sealing device for reclosing the puncture.

4. An apparatus for inserting accessory ingredients into the sterilized contents of sealed containers which includes a sterilizing zone through which the containers enter an adjacent sterile chamber in which they are operated upon, a feeding device within this chamber for inserting accessory ingredients into the container through an opening caused in the container wall, and a sealing device for reclosing the opening within the sterile chamber.

5. An apparatus for inserting accessory ingredients into the sterilized contents of sealed containers which includes a sterile working chamber, at least one injection needle within this chamber, means for causing the injection needle to penetrate the container wall and for removing it again therefrom, means for inserting the accessory ingredients through the injection needle into the container, and a sealing device for reclosing the penetration also within the sterile chamber.

6. An apparatus for inserting accessory ingredients into the sterilized contents of sealed containers which includes a sterile working chamber through which the containers pass and wherein they are operated upon, a feeding device within this chamber for puncturing the containers and inserting accessory ingredients through the puncture, and a device for resealing the container within the chamber.

7. The method of inserting accessory ingredients into the sterilized contents of a sealed container comprising the steps of sterilizing the container wall, puncturing the same, inserting accessory ingredients into the container, and closing the opening, the puncturing, inserting and reclosing being performed within a sterile chamber.

8. The method of inserting accessory ingredients into the sterilized contents of a sealed container comprising the steps of sterilizing the container wall, puncturing the same, inserting accessory ingredients through the puncture, and resealing the container, the puncturing, inserting and resealing being performed within a sterile chamber at a temperature which is innocuous to the accessory ingredients.

9. An apparatus for inserting accessory ingredients into the sterilized contents of sealed containers which includes a sterile working chamber, means for the formation of a flame wall closing the entrance and outlet openings of this chamber, and within this chamber a feeding device for puncturing the container wall and for inserting accessory ingredients into the container, and a sealing device for reclosing the puncture.
